UNITED STATES PATENT OFFICE.

ANDREW LANGSTAFF JOHNSTON, JR., OF RICHMOND, VIRGINIA.

SAFETY-RAZOR.

1,398,193.

Specification of Letters Patent.

Patented Nov. 22, 1921.

Application filed April 27, 1920. Serial No. 377,063.

To all whom it may concern:

Be it known that I, ANDREW LANGSTAFF JOHNSTON, Jr., a citizen of the United States, residing at Richmond, in the county of Henrico and State of Virginia, have invented 5 certain new and useful Improvements in Safety-Razors; and I do hereby declare the following to be a full, clear and exact description of the invention, such as will enable 10 others skilled in the art to which it appertains to make and use the same.

The present invention relates to improvements in safety razors, and has for an object to provide an improved razor in which the 15 blade may be retained in its assembled condition on the razor holder without the necessity of removing the same for purposes of stropping, and which is used in conjunction with an improved form of guard adapted 20 to catch the lather as the shaving operation proceeds, the blade being movably mounted so as to swing free of the guard to permit the removal of accumulations of lather and permit drying.

Another object of the invention lies in an 25 improved mounting for the blade which permits it to have the above referred to pivotal adjustment, and which is so constructed and arranged as to be capable of operation in 30 a quick and facile manner.

A further object of the present invention resides in providing in conjunction with the 35 pivotal mounting of the blade and the means for accomplishing the swinging thereof, certain parts by which the adjustment of the blade with respect to the guard may be had.

In the accompanying drawings forming 40 a part of this application, and in which similar reference symbols indicate corresponding parts in the several views:

Figure 1 is an enlarged side view of an improved razor constructed according to the present invention and showing the blade in two positions.

Fig. 2 is an enlarged rear view of the holder, showing the blade in the raised position and with a portion of the handle cut away.

Fig. 3 is an enlarged front view of the 50 razor with the blade closed and with the handle broken away.

Fig. 4 is a similar view with the blade in the raised position.

Fig. 5 is a perspective view of a blade 55 that may be used in the improved razor.

Fig. 6 is a perspective view, with parts in section, of the improved holder.

Fig. 7 is a vertical sectional view showing the guard holder and with the blade in the raised position.

Fig. 8 is a similar view with the blade closed; and

Fig. 9 is a fragmentary side view showing the method of applying and removing the blade.

Fig. 10 is a view in elevation of a slightly modified form of razor and clip.

Fig. 11 is an edge view thereof.

Fig. 12 is a fragmentary perspective view 65 of the same.

Fig. 13 is an enlarged fragmentary elevation of the improved means for releasably holding the blade in the clip.

Fig. 14 is a perspective view of the blade; 70 and

Fig. 15 is a side view of the improved device assembled on the razor holder.

Referring more particularly to the drawings, 1 designates the handle of the razor which may be of any suitable construction and ornamental form, and 2 designates the holder for the blade which is combined with the guard 3. This holder 2 and guard 3 are preferably formed of a piece of sheet metal bent into a substantially trough-shape, as 80 indicated in Fig. 1, to form a receptacle beneath the blade for catching the lather as the blade edge is moved over the face.

As indicated in Figs. 3 and 4, the guard 3 is provided with suitable perforations or 90 slots 4 in the free edge thereof where the sharp edge of the blade 5 is adapted to rest thereagainst. These slots or perforations 4 permit the passage of the lather into the trough.

Cleats 6 are formed at opposite ends of the guard 3, and are for the purpose of receiving the blade edge 5 when the same is in the operative position in readiness for shaving. These slots may be formed in any 100 suitable manner, and I do not wish to be restricted to any particular arrangement, as the guard may be varied in numbers of ways.

The holder 2 is more particularly shown in Fig. 6, and extends about the rear of the 105 razor and in a substantially semi-circular form together with the guard 3. At its upper side edges the guard 3 is provided with forwardly projecting bearings 7, preferably made in one piece with the sheet 110

metal of the holder, and extending at right angles thereto. The bearings 7 are made enlarged at their upper ends where they are provided with elongated slots 8 having openings 9 through the tops thereof to receive the blade, as hereinafter described.

The holder 2, centrally thereof and at its upper edge, is provided with rolled-over eyes 10 between which is made a recess 11.

- 10 In the recess is mounted a thumb wheel 12 having a knurled or other suitable edge 13 for facilitating its turning. A shaft 14 is journaled in the rolled over eyes 10 to support the thumb wheel 12 for rotary motion 15 therebetween, the recess 11 being for the purpose of receiving said wheel and permitting it to extend through the holder 2 for coming in contact with the blade, as later referred to.

- 20 A pin 15 is made to project from the side of the thumb wheel 12 for the purpose of coming into contact with the rear wall of the holder 2 to limit the turning movement of the wheel when it arrives in the position, 25 for instance, shown in Fig. 8. A cam nose 16 is provided on the thumb wheel 12 and is made to extend forwardly therefrom. This cam nose may be of any suitable shape for accomplishing the purpose for which it 30 is intended, and it is with advantage designed as shown in Figs. 7 and 8, where it is clear that the under side of the nose 16 may also act as a stop by engaging the wall of the holder 2 just beneath the recess 11.

- 35 Flat springs 17 are secured at their lower ends 18 in any desirable manner to the outside faces of the bearings 7, and they are formed with semi-cylindrical depressions 19 inward of their upper ends 1, as shown in 40 Fig. 9, extending beyond the upper ends of the bearings 7. The semi-cylindrical depressions 19 are formed at substantially the same elevation as the slots 8, and they coöperate therewith to removably hold the blade 45 therein, as presently described.

- The blade 5 is shown more particularly in Fig. 5, and is reinforced by a binder strip 20 of suitable metal which is bent substantially U-shape, clamping the inner edge of 50 the blade 5 therebetween. A small steel wire is clamped in the bight of the binder strip 20, and has its ends projecting therebeyond and beyond the side edges of the blade 5 to form trunnions 21 on which the 55 blade may pivot.

- In practice, the blade 5, assembled with the binder 20 and the trunnions 21 as shown in Fig. 5, is applied in the manner shown in Fig. 9 to the projecting upper ends of 60 the spring arms 17; and such arms are pressed downwardly thereby, yielding in the manner indicated in dotted lines in Fig. 1, so that the trunnions 21 may be brought to positions above the openings 9 to the slots 65 8. The trunnions are then moved down-

wardly through such openings and into the slots 8, pressure being thereupon released from the spring arms 17 which act to return to the initial upper position, thus effectually clamping the trunnions 21 in the 70 upper portions of the slots 8.

The trunnions 21 are free to turn in the slots 8 so that the blade may be swung downwardly to the position also shown in dotted lines in Fig. 1. For accomplishing this result the binder strip 20 of the blade 5 is preferably knurled, as indicated at 22 in Fig. 5, such knurled portion 22 being in contact with the knurled edge 13 of the thumb wheel 12.

A rotation of the thumb wheel 12 in a clockwise direction will therefore operate to swing the blade 5 downward to close the mouth of the trough formed by the holder 2 and guard 3. After the blade has been so 85 swung down and the cutting edge thereof brought into alignment with the clips 6, the cam nose 16 on the thumb wheel is brought actively into engagement with the knurled portion 22 of the blade binder, and the further movement of this cam nose will force the entire blade assembly downwardly in opposition to the spring arms 17. The blade is thus moved into the clips 6 and into a proper position with respect to the guard 90 slots 4, so that it is now in a position for 95 shaving.

A flat tip 23 on the cam nose 16 engages against the knurled portion 22 of the blade binder, as indicated in Fig. 8, and locks the 100 blade in the operative position. Of course the thumb wheel 12 may be turned to various positions, in order to adjust the blade edge with respect to the guard.

The blade 5 may be removed from the 105 holder at any time by releasing the pressure of the spring arm 17 and lifting the trunnions 21 through the openings 9 in the slots 8; but it is preferred that this razor be used in conjunction with a case which contains 110 a stropping device, forming the subject-matter, of a separate application, and where this is done the blade 5 may remain in place on the holder and simply be swung up to the full line position shown in Fig. 1, where the 115 blade may enter between the stropping rolls of the case.

Referring more particularly to Figs. 10 to 15 inclusive, the blade 30 shown is of the type now generally in use on the auto-strap 120 razor, and is provided with the notches 31 in its opposite ends. The holding clip is rolled centrally to provide a cylindrical spring portion 32 and side clamps 33 and 34 releasably held together by the action of the 125 spring portion 32. The inner edge of the blade 30 is adapted to be received between the clamps 33 and 34, as shown in Fig. 11.

In one end one of the clamps, for instance 33, is provided with a notch 35 to receive the 130

turned over end 36 on the adjacent end of the companion clamp 34. The opposite end of the clamp 33 is cut away as indicated at 37, while the proximate end of the clamp 5 34 is punched or otherwise formed with a lug or projection 38 made of substantially triangular shape and having a sloping or cam surface 39 adapted to be engaged by the blade 30 as it is moved into the clip.

10 The clip is, of course, made of spring metal so that the end of the clamp 34 which carries the projection 38 will be allowed to recede away from the blade when the latter engages the cam face 39. This spring action will be assisted by the provision of a slot 40 made along the upper edge of the clamp 34 and between same and the cylindrical spring portion 32. As soon as the blade 30 is moved all the way into the clip 20 the notch 31 will be presented to the projection 38 so that the spring action will move such projection into the notch and the abrupt wall 41 will act to effectively bind the blade in place.

25 A tab or thumb piece 42 projects outwardly from the end of the clamp 34 so that such end may be sprung back manually when it is desired to remove the blade. The cylindrical spring portion 32 of the clip is 30 continued outwardly at both ends beyond the clamps to provide trunnions 43 and 44, the lower ends being rolled together as indicated at 45 in order that the trunnions may assume a true cylindrical shape.

35 The trunnions are fitted in slots 46 made in the holder 47 which is similar to the holder 2 described in connection with the first form of the invention, there being this difference that the slot 46 is closed as shown 40 in Fig. 15, whereas in the former case it was left open.

By having the slot 46 closed the trunnions 43 and 44 are permanently held therein, the holder being originally bent axially 45 from the trunnions. It is, of course, not necessary to have the clip removable from the holder 47, as the blade is easily withdrawable from the clip.

It is obvious that those skilled in the art 50 may vary the details of construction and arrangements of parts without departing from the spirit of my invention, and therefore I do not wish to be limited to such features except as may be required by the 55 claims.

I claim:

1. An improved safety razor comprising a handle, a holder carried thereby and provided with a guard, and a blade swingingly 60 mounted in said holder and adapted to reciprocate in a rectilinear path to and from the guard, and means to cause the swinging and reciprocating movement of the blade, substantially as described.

2. An improved safety razor comprising a

handle, a holder carried thereby, a guard on the holder, a blade removably mounted in the holder and fitted to swing to and from the guard, said blade also mounted for reciprocating movement in a rectilinear path, 70 and a cam device having a portion meshing with said blade to swing and reciprocate the same successively, substantially as described.

3. An improved safety razor including a holder, slotted bearings thereon having 75 openings therethrough, a blade having trunnions removably fitted in said slotted bearings and provided with a knurled portion, a thumb wheel having a knurled edge mounted in said holder and in mesh with the knurled portion of the blade whereby turning of the thumb wheel may swing the blade in the slotted bearings, and a guard for receiving the cutting edge of the blade when in operative position, substantially as described. 80

4. An improved safety razor including a holder having slotted and open bearings, spring arms associated therewith and having semi-cylindrical depressions and ends projecting beyond the bearings, a blade having 90 trunnions adapted to engage the projecting ends of the springs to force the same to a position allowing of the insertion of the trunnions in the open slotted bearings, means for turning the blade in the trunnions, and 95 a guard against which the cutting edge of the blade is adapted to rest when in operative position, substantially as described.

5. An improved safety razor comprising a holder, a blade having notches, a clip for 100 holding the blade composed of a pair of clamps adapted to receive the blade therebetween, said clip having means at one end to engage the notch of the blade at that end, means on one of the clamps at the opposite 105 end of the clip for engaging in the other notch of the blade, said means being rigid with the clamp to which it is attached, the end of the clamp to which said means is attached being yieldable away from the blade, 110 and a part extending from said clamp beyond the blade edge for engagement by the finger, substantially as described.

6. An improved safety razor comprising a holder, a blade having notches in its side 115 edges, a clip for holding the blade comprising a pair of clamps for receiving the notched portion of the blade therebetween, said clip having means at one end for engaging one of the notches of the blade, one of the clamps 120 at the other end of the clip provided with a projection adapted to enter the other notch of the blade, said clip being slotted along the portion of the clamp carrying said projection, and a finger piece extending from the portion of the clamp carrying said projection outwardly beyond the edge of the blade, substantially as described.

7. An improved safety razor including a 125 holder, a clip mounted in said holder and 130

embodying a pair of clamps, a blade adapted to be removably inserted between said clamps, said blade having notches in its ends, means to engage one of the notches in the 5 blade, one of the clamps being cut away at its other end, the other clamp at the end adjacent such cut away portion having a projection adapted to occupy the other notch in the blade, said projection having a cam 10 face adapted to be acted on by the blade to remove the projection from the path of the blade in moving the same into the clip, said projection also having an abrupt wall to engage the blade when the same is once in the 15 final position in the clip, and means for manually removing the projection from said notch in the blade, substantially as described.

8. An improved safety razor comprising a holder, a blade having notches in its edges, a 20 clip for holding the blade comprising a pair of spring clamps adapted to come together

on opposite sides of the blade, means at one end of the clamp for engaging with the adjacent notch in the blade, the other end of the clip having a projection pressed out from 25 one of the clamps for engaging with the other notch in the blade, said projection having an inclined wall adapted to guide the blade thereinto and provided with an abrupt wall for locking against the wall of the 30 notch in the blade, substantially as described.

9. An improved safety razor including a holder having slotted and open bearings, a blade having trunnions rotatably and slidably fitted in said bearings, means for rotating and sliding the trunnions in said bearings, a guard, and lugs on the guard adapted to receive the edges of the blade when the same is slid forwardly, substantially as described

ANDREW LANGSTAFF JOHNSTON, Jr.
